UNITED STATES PATENT OFFICE.

FREDERICK S. PINKUS, OF NEW YORK, N. Y.

DESIGN FOR A TEXTILE FABRIC.

49,582.

Specification for Design. Patented Aug. 29, 1916.

Application filed April 28, 1916. Serial No. 94,266. Term of patent 7 years.

To all whom it may concern:

Be it known that I, FREDERICK S. PINKUS, a citizen of the United States, residing at New York, in the county of New York and State of New York, have invented a new, original, and ornamental Design for Textile Fabrics, of which the following is a specification, reference being had to the accompanying drawing, forming part thereof.

The drawing is an elevation of a piece of a textile fabric exhibiting my new design.

This invention relates to a new, original and ornamental design for textile fabrics generally, but more particularly for fabrics which may serve for pillow cases, sheeting,

curtains or similar purposes; and comprises, generally stated, the characteristic features shown in the drawing.

The numeral 1 upon the drawing indicates ribs or cords; 2 indicates the open-work or fancy weave; and 3 indicates open-work in imitation of hem-stitching. The features of the design are arranged in parallel or banded relation.

I claim:

The ornamental design for a textile fabric, substantially as shown and described.

In witness whereof I affix my signature.

FREDERICK S. PINKUS.
